United States Patent Office.

SAMUEL H. COWLES, OF OAKVILLE, CONNECTICUT.

Letters Patent No. 75,866, dated March 24, 1868.

IMPROVED CAR-COUPLING.

The Schedule referred to in these Letters Patent and making part of the same.

TO ALL WHOM IT MAY CONCERN:

Be it known that I, SAMUEL H. COWLES, of Oakville, in the county of Litchfield, and in the State of Connecticut, have invented a certain new and useful Improvement in Car-Couplings; and I do hereby declare that the following is a full, clear, and exact description thereof, reference being had to the accompanying drawings, and the letters of reference marked thereon. In the annexed drawings, making a part of this specification—

Figure 1 represents a section of a car-coupling, showing the construction and relative position of its parts. A represents the draw-head, provided with a flaring mouth and a chamber, in which is pivoted the draw-hook B, and is fastened the slotted guide C. The draw-head A may be constructed in any of the ordinary forms and manner. B represents a peculiar-shaped draw-hook, as seen in the drawings, pivoted in the chamber of the draw-head A, and is provided with a steel or other spring, x, inserted in its back or upper side in such manner as will hold, and for the purpose of keeping the front end of said hook B down close to the lower side of the mouth of the draw-head A. It is also provided with a vertical pin or rod, g, which passes up through the top of the draw-head, and is designed as a convenient handle for the purpose of raising up the front end of the hook B to uncouple cars, whenever it may be desired to do so. C represents a metallic guide, screwed or secured to the top of the chamber in the draw-head A, and provided with a slot, e, in which fits and works the hook B, and is designed to hold the same steady and brace it against lateral strains. It is placed far enough back from the mouth of the draw-head A, so that its face or front side is behind and nearly parallel with the catch of the hook B, and of such length that the link D may pass beneath it when pushed too far into the chamber of the draw-head A. The outer or front end of the hook B is bevelled from its upper side, so that when the link D strikes it, it is pressed up, and the said link passes under and is caught by the said hook B.

I am aware that various-shaped hooks have been used within the draw-head before, some of which are constructed similar to the one herein described.

What I claim, and desire to secure by Letters Patent, is—

The slotted metal guide C placed within the mouth of the draw-head A, as specified, and used in combination with the pivoted hook B, the front of which is bevelled from top to bottom, all constructed and operating as set forth.

In testimony that I claim the foregoing, I have hereunto set my hand, this 17th day of December, 1867.

SAMUEL H. COWLES.
